ARTIFICIAL ARM

John Maria Hauser, Takoma Park, Md., assignor
to House of Modern Medical Appliances Company, Takoma Park, Md., a firm

Application March 22, 1949, Serial No. 82,730

15 Claims. (Cl. 3—12)

1

This invention is a novel improvement in artificial arms actuated by flexible cords attached to shoulder harnesses, the invention particularly relating to the elbow joint of such artificial arms, the joint being so designed that when the forearm is hinged upwardly with respect to the upper arm portion, the hinge will automatically bind in the position into which it has been swung to prevent lowering of the forearm until a pull is exerted on the cord by manipulation of the shoulder harness by the wearer to release the binding means at the elbow joint, whereupon the forearm may again be lowered to its fully outstretched limit.

A further object of the invention is to provide a novel means for binding and releasing the hinged elements of the upper arm and forearm positions at the elbow joint.

I will explain the invention with reference to the accompanying drawing which illustrates one practical embodiment thereof, to enable others familiar with the art to adopt and use the same; and will summarize in the claims, the novel features of construction, and novel combinations of parts, for which protection is desired.

In said drawing:

Figure 1 is a side elevation of the artificial arm showing the forearm in normal outstretched position with respect to the upper arm portion.

Fig. 2 is a front elevation of the parts shown in Fig. 1.

Fig. 3 is a side elevation, partly in section, through the elbow hinge, showing the binding and releasing means, the forearm being shown in substantially right-angle relation to the upper arm portion.

As shown, the artificial arm preferably comprises an upper arm socket portion 1 which may be of conventional shape adapted to receive the shoulder arm stub of the wearer, also a forearm portion 2 which may also be of conventional shape, the parts being connected by my novel elbow hinge so as to permit the forearm portion to be pivoted from a position in substantial alignment with the upper arm portion 1, as shown in Fig. 1, into a position at substantially right angles thereto, as shown in Fig. 3.

The hinge preferably comprises a pair of spaced ear elements 3 extending downwardly from the lower end of the upper arm portion 1 in parallel relation, as shown in Fig. 2, the same having at their lower ends aligned bores 3a adapted to receive a pivot pin 4, the lower ends of ears 3 being also provided with arcuate portions 3b on their forward edges thereof disposed

coaxially of the pin 4 for the purpose hereinafter described, said arcuate portions 3b being substantially 180 degrees in length and having at their lower ends limiting pins 3c for the purpose hereinafter described.

Hingedly mounted on the pin 4 between the ears 3 is a substantially circular plate 5 having an enlarging arcuate portion 5a beyond which extends a substantially triangular portion 5b having its axis offset from the axis of pin 4 and having its base overlying the arcuate portions 3b of the ears 3, said plate 5 also having an extension 5c which is secured to an arm or bracket 6 by screw 7 or the like, the bracket 6 being bifurcated as at 6a (Fig. 2) and fitting within the rear end of the forearm portion 2 and being secured thereto by screws 8 or the like. As shown in Fig. 3, the angle between the adjacent edges of extension 5c and the triangular portion 5b is acute (approximately 30°), for the purpose hereinafter described.

In the plate 5 opposite the arcuate portion 3b is an opening 5d (Fig. 3) through which passes a pin 9 of sufficient length to seat directly upon the arcuate portions 3b so as to bind the plate 5 against the arcuate portions 3b when the pin 9 is shifted towards the ears 3, and thereby lock the forearm portion 2 in adjusted angularity with respect to the upper arm portion 1.

Pivoted at 10 on the triangular portion 5b at a point beyond the pin 9 is a pin actuating member 11 of substantial U-shaped cross-section having side legs overlying the faces of portion 5b which are perforated to receive the pivot pin 10, the legs being connected together as at 11a around the edge of triangular portion 5b adjacent the arm 5c. Member 11 is provided with slots 11b extending upwardly from the lower edges of the side legs receiving the ends of the pin 9, whereby as the member 11 is pivoted on pin 10, the pin 9 will be shifted substantially tangentially of the arcuate portions 3b, thereby releasing the binding grip of pin 9 on said arcuate portions 3b, thus permitting the forearm 2 to be swung downwardly into outstretched relation with respect to the upper arm portion 1, as indicated in Fig. 1, the movement being limited by contact of pin 9 against the limiting pins 3c hereinbefore described. The member 11 is normally yieldably sprung so as to maintain the pin 9 in binding engagement with the arcuate portions 3b.

On the outer end of the member 11 is pivoted, as at 12, a member 13 which is secured to a flexible cord 14 which lies in a groove 5x pro-

vided therefor in the arcuate portion 5a of plate 5, the groove serving as a guide therefor. The cord 14 passes under a grooved pulley 16 which is journaled on a pin 17 between the ears 3 of the upper arm portion 1, the cord 14 being actuated by the shoulder harness (not shown) of the wearer, so that as cord 14 is pulled, the member 11 will be swung downwardly toward the plate 5.

The member 11 is normally yieldably urged in the direction to bind the pin 9 on the arcuate portions 3b by means of a flat spring 18 which is confined between the face of the triangular portion 5b and the wall 11a of the member 11, with its lower end contacting the adjacent edge 15 of the arm 5c, and its upper end contacting the under side of the member 13.

By the above construction, since the lower end of spring 18 engages at an obtuse angle the upper face of the arm 5c, it is obvious that the member 11 will be normally urged to rotate in a clockwise direction (Fig. 3) about the pivot 10 so as to bind the pin 9 against the arcuate portions 3b. However, as soon as the flexible cord 14 is pulled, the member 11 will be pivoted on the pin 10 in an anti-clockwise direction sufficiently to move the pin 9 substantially tangentially out of binding engagement with the arcuate portions 3b.

By the above construction the wearer may at any time move the forearm portion 2 by contact with a fixed object upwardly into desired angular relation with respect to the upper arm portion 1, and said forearm portion will be frictionally bound by the pin 9 so as to remain in such angular position until a pull on the flexible cord 14 is exerted which will pivot the member 11, thereby releasing the pin 9 from said binding engagement with the arcuate portions 3b.

I do not limit my invention to the exact form shown in the drawing, for obviously changes may be made therein within the scope of the claims.

I claim:

1. In an artificial arm having an upper arm portion and a forearm portion, an elbow joint connecting said portions comprising an ear extending from the upper arm portion, a hinge pin carried by said ear, the forward edge of the ear being arcuate coaxially of the pin, a plate journaled on the pin, said plate having a substantially triangular portion with its base substantially overlying the arcuate portion of the ear and its apex outermost; an arm on said plate connected with the forearm portion, the angle between the adjacent edges of the arm and triangular portion being acute; a locking pin movably carried by the plate and adapted to seat upon said arcuate portion; means journaled on the triangular portion for shifting the locking pin substantially tangentially of the arcuate portions; means for normally yieldably urging said shifting means to bring the locking pin into binding contact with the said arcuate portion; and means for moving the said shifting means in the opposite direction to release said binding contact.

2. In an artificial arm as set forth in claim 1, a lug on the arcuate portion of the ear adapted to be engaged by the locking pin to limit the hinging movement.

3. In an artificial arm as set forth in claim 1, said shifting means comprising a substantially U-shaped member having side legs provided with slots in their lower edges receiving the locking pin, the base of the member being disposed between the adjacent edges of the triangular portion and the arm of the plate.

4. In an artificial arm as set forth in claim 1, said shifting means comprising a substantially U-shaped member having side legs provided with slots in their lower edges receiving the locking pin, the base of the member being disposed between the adjacent edges of the triangular portion and the arm of the plate; and said urging means comprising a flat spring confined between the base of the U-shaped member and the adjacent face of the triangular portion, and having one end slidably engaging the adjacent face of the arm of the plate at an acute angle.

5. In an artificial arm as set forth in claim 1, said shifting means comprising a substantially U-shaped member having side legs provided with slots in their lower edges receiving the locking pin, the base of the member being disposed between the adjacent edges of the triangular portion and the arm of the plate; said urging means comprising a flat spring confined between the base of the U-shaped member and the adjacent face of the triangular portion, and having one end slidably engaging the adjacent face of the arm of the plate at an acute angle; and said moving means comprising a member pivoted at the outer end of the U-shaped member, the under side of which is engaged by the opposite end of the flat spring, and a flexible cord attached to said pivoted member and extending through guides whereby as the cord is pulled the pivoted member will be swung against the action of the flat spring.

6. In an artificial arm having an upper arm portion and a forearm portion, an elbow joint connecting said portions comprising a pair of spaced parallel ears extending from the upper arm portion, a hinge pin carried by said ears, the forward edges of the ears being arcuate coaxially of the pin; a plate between the ears journaled on the pin, said plate having a substantially triangular portion with its base substantially overlying the arcuate portions of the ears and its apex outermost; an arm on said plate connected with the forearm portion, the angle between the adjacent edges of the arm and triangular portion being acute; said plate having a slot therein opposite the arcuate portions of the ears; a locking pin extending through said slot and adapted to seat upon said arcuate portions; means journaled on the triangular portion for shifting the locking pin substantially tangentially of the arcuate portions; means for normally yieldably urging said shifting means to bring the locking pin into binding contact with the said arcuate portions; and means for moving the said shifting means to release said binding contact.

7. In an artificial arm as set forth in claim 6, lugs on the arcuate portions of the ears adapted to be engaged by the locking pin to limit the hinging movement.

8. In an artificial arm as set forth in claim 6, said shifting means comprising a substantially U-shaped member having side legs provided with slots in their lower edges receiving the locking pin, the base of the member being disposed between the adjacent edges of the triangular portion and the arm of the plate.

9. In an artificial arm as set forth in claim 6, said shifting means comprising a substantially U-shaped member having side legs provided with slots in their lower edges receiving the locking pin, the base of the member being disposed between the adjacent edges of the triangular portion and the arm of the plate; and said urging means comprising a flat spring confined between

the base of the U-shaped member and the adjacent face of the triangular portion, and having one end slidably engaging the adjacent face of the arm of the plate at an acute angle.

10. In an artificial arm as set forth in claim 6, said shifting means comprising a substantially U-shaped member having side legs provided with slots in their lower edges receiving the locking pin, the base of the member being disposed between the adjacent edges of the triangular portion and the arm of the plate; said urging means comprising a flat spring confined between the base of the U-shaped member and the adjacent face of the triangular portion, and having one end slidably engaging the adjacent face of the arm of the plate at an acute angle; and said moving means comprising a member pivoted at the outer end of the U-shaped member the under side of which is engaged by the opposite end of the flat spring, and a flexible cord attached to said pivoted member and extending through guides whereby as the cord is pulled the pivoted member will be swung against the action of the flat spring.

11. In an artificial arm having an upper arm portion and a forearm portion, an elbow joint connecting said portions comprising a pair of spaced parallel ears extending from the upper arm portion, a hinge pin carried by said ears, the forward edges of the ears being arcuate throughout substantially 180° in length coaxially of the pin; a plate between the ears journaled on the pin, said plate having a substantially triangular portion with its base substantially overlying the arcuate portions of the ears and its apex outermost; an arm on said plate connected with the upper end of the forearm portion, the angle between the adjacent edges of the arm and triangular portion being acute; said plate having a slot therein opposite the arcuate portion of the ears; a locking pin extending through said slot and adapted to seat upon said arcuate portions; means journaled on the triangular portion beyond the locking pin for shifting the locking pin substantially tangentially of the arcuate portions; means for normally yieldably urging said shifting means to bring the locking pin into binding contact with the said arcuate portions; and means

for moving the said shifting means in the opposite direction to release said binding contact.

12. In an artificial arm as set forth in claim 11, lugs on the arcuate portions of the ears adapted to be engaged by the locking pin to limit the hinging movement.

13. In an artificial arm as set forth in claim 11, said shifting means comprising a substantially U-shaped member having side legs provided with slots in their lower edges receiving the locking pin, the base of the member being disposed between the adjacent edges of the triangular portion and the arm of the plate.

14. In an artificial arm as set forth in claim 11, 15 said shifting means comprising a substantially U-shaped member having side legs provided with slots in their lower edges receiving the locking pin, the base of the member being disposed between the adjacent edges of the triangular portion and the arm of the plate; and said urging means comprising a flat spring confined between the base of the U-shaped member and the adjacent face of the triangular portion, and having one end slidably engaging the adjacent face of

25 the arm of the plate at an acute angle.

15. In an artificial arm as set forth in claim 11, said shifting means comprising a substantially U-shaped member having side legs provided with slots in their lower edges receiving the locking

30 pin, the base of the member being disposed between the adjacent edges of the triangular portion and the arm of the plate, and said urging means comprising a flat spring confined between the base of the U-shaped member and the adjacent face of the triangular portion, and having one end slidably engaging the adjacent face of

35 the arm of the plate at an acute angle, and said moving means comprising a member pivoted at the outer end of the U-shaped member the

40 under side of which is engaged by the opposite end of the flat spring, and a flexible cord attached to said pivoted member and extending through guides whereby as the cord is pulled the pivoted member will be swung against the action of the flat spring.
